UNITED STATES PATENT OFFICE.

JOSEPH R. PIPER AND WILLIAM R. SHRECKER, OF WORDEN, ILLINOIS.

PISTON.

1,411,512.

Specification of Letters Patent. Patented Apr. 4, 1922.

Application filed August 26, 1921. Serial No. 495,259.

To all whom it may concern:

Be it known that we, JOSEPH R. PIPER and WILLIAM R. SHRECKER, citizens of the United States, residing at Worden, in the county of 5 Madison, State of Illinois, have invented a new and useful Piston, of which the following is a specification.

This invention relates to pistons for explosive engines, one of its objects being to 10 provide a piston made of aluminum alloy and of iron. Heretofore attempts have been made to construct pistons of the two metals but, owing to the difference in the coefficient of expansion it has not been possible to 15 cure a tight joint between the two metals and, consequently, leakage has occurred.

One of the objects of the invention is to provide a piston having the trunk thereof made of aluminum alloy while the skirt of 20 the piston is formed of gray iron, there being an expanding ring likewise formed of gray iron and so mounted as to properly seal the piston and insure its correct working within the cylinder.

25 A further object is to provide a piston which, by having a trunk formed of aluminum alloy, will not collect carbon, there being means, however, for protecting the aluminum so that no part of the trunk is exposed to wear.

A still further object is to provide a piston which is light and the wearing parts of which can be replaced easily at small cost.

With the foregoing and other objects in view which will appear as the description proceeds, the invention resides in the combination and arrangement of parts and in the details of construction hereinafter described and claimed, it being understood that, within 40 the scope of what is claimed, changes in the precise embodiment of the invention shown can be made without departing from the spirit of the invention.

In the accompanying drawings the preferred form of the invention has been shown.

In said drawings—

Figure 1 is an elevation of a piston constructed in accordance with the present invention, a portion of the skirt or band being 50 broken away.

Figure 2 is a central longitudinal section through the piston.

Figure 3 is a section on line 3—3, Figure 2.

Referring to the figures by characters of 55 reference 1 designates the trunk of the piston, the same being formed of an aluminum

alloy and having opposed bearings 2 for the pin 3 of the piston rod. Formed in the outer face of this trunk adjacent the closed end of the piston are annular grooves 4 for the reception of piston rings 5 of the usual construction. A broader groove 6 is also formed in the outer surface of the trunk and has one wall beveled and undercut as shown at 7 while the opposed wall is at right angles to 65 the outer surface of the trunk, as shown at 8. Engaging the undercut wall 7 of this groove is a wedging ring 9. Another annular groove 10 is formed in the outer surface of the trunk adjacent that end remote from 70 the closed end of the piston and the diameter of the trunk is reduced between the grooves 8 and 10 so as to receive the skirt 11 of the piston. This skirt is formed preferably of 75 gray iron and is provided at one end with an inwardly extending rib 12 adapted to be seated in the groove 10. At the other end the skirt has an inwardly extending rib 13 adapted to be seated in the groove 6, this end of the skirt and the corresponding face of 80 the rib 13 being beveled so as to engage the wedging ring 9. The longitudinal edges of the skirt 11 are cut away to form lips 14 which lap as shown in Figure 3 so as thus to 85 provide a sealed connection between the said portions of the skirt.

Obviously when the piston is in use the skirt 11 will properly engage the wall of the cylinder and insure a tight connection. If 90 the skirt becomes worn it can be removed readily and another substituted therefor. Thus the trunk of the piston is protected at all times and can be made of an aluminum alloy. Any variation in the relative position 95 of the parts due to the difference of their coefficients of expansion will be automatically compensated for by the wedging ring 9. This wedging ring also automatically takes up end wear upon the skirt. The skirt or sleeve 11 also prevents the end of the pin 3 100 from scarring the wall of the cylinder. The space between the skirt or sleeve 11 and the trunk will be filled with oil which thus forms a cushion and prevents the piston from 105 flapping while reciprocating. This oil is admitted to the space between the skirt and the body or trunk through openings 15 formed in the trunk.

What is claimed is:—

1. A piston including a trunk having 110 spaced annular grooves, that portion of the trunk between the grooves being of reduced

- diameter, a wedging ring seated in one of the grooves, a skirt surrounding the reduced portion of the trunk and having inwardly extending ribs seated within the respective 5 grooves, one of said ribs engaging the wedging ring, there being a space between the skirt and the trunk for the reception of oil, there being openings through the trunk and opening into this space.
- 10 2. The combination with a trunk having spaced grooves, that portion of the trunk between the grooves being of reduced diameter, of a tapered wedging ring seated within one of the grooves, said ring being lapped 15 by one of the walls of the groove, said wall and corresponding face of the ring being beveled, a skirt surrounding the reduced portion of the trunk and having inwardly extending ribs seated within the spaced 20 grooves, one end of the skirt engaging the wedging ring, there being an annular oil receiving space between the skirt and the trunk and communicating with the interior of the trunk.
- 25 3. The combination with a trunk having annular spaced grooves, that portion of the
- trunk between the grooves being of reduced diameter, and a piston pin seated at its ends within the reduced portion of the trunk, of a wedging ring seated in one of the grooves, 30 said groove having an undercut wall engaging the ring for deflecting the ring toward the other wall of the groove when the ring is expanded in the groove, a skirt having lapping edges and surrounding the reduced 35 portion of the trunk, inwardly extending ribs upon the skirt and seated within the respective grooves, one of said ribs and the corresponding end of the skirt engaging the wedging ring, there being an oil receiving 40 space between the skirt and the trunk and communicating with the interior of the trunk.

In testimony that we claim the foregoing as our own, we have hereto affixed our signatures in the presence of two witnesses.

JOSEPH R. PIPER.
WILLIAM R. SHRECKER.

Witnesses:

MABEL F. UNGER,
